UNITED STATES PATENT OFFICE.

LOUIS E. LEYENS, OF VICKSBURG, MISSISSIPPI.

PRINTING MACHINE AND MEANS FOR MAKING THE SAME.

Application filed July 19, 1920. Serial No. 397,184.

To all whom it may concern:

Be it known that I, LOUIS E. LEYENS, a citizen of the United States, residing at Vicksburg, in the county of Warren and 5 State of Mississippi, have invented a certain new and useful Improvement in Printing Machines and Means for Making the Same, of which the following is a full, clear, concise, and exact description, reference being 10 had to the accompanying drawings, forming a part of this specification.

My invention relates to improvements in printing machines and means for making the same and is especially concerned with 15 improvements in that type of machine commercially known as the multigraph.

It is often desirable to use cuts or prints in connection with the multigraph machine. Heretofore these cuts or prints have been 20 prepared by the electrotype process and as a result they are not only expensive but more or less delay is experienced in procuring them.

The cuts or prints formed by the electrotype process are of annular cylindrical shape 25 and are secured to the segment of the printing machine either by means of bands engaging the edges of the prints or cuts or where the prints or cuts are of less width 30 than the printing segment, by means of clips having T-shaped heads for engaging the correspondingly shaped slots in the segment of the machine and an overhanging lip or projection for engaging the edge of the print or 35 cut. Considerable difficulty has been experienced in the use of such cuts because of their tendency to slip on the printing segment and thus throw them out of alinement. Furthermore, the reproductions produced 40 by cuts secured to the printing segment heretofore employed are apt to be more or less indistinct, due to a slight movement of the cut during the printing operation.

The objects of my invention are:

45 (1) To provide a cut having novel means formed integrally therewith for securing the cut to the printing segment of a printing machine, whereby the cut can be easily secured to and detached from the printing segment and by means of which the cut will be rigidly held against displacement during the printing operation;

50 (2) To provide a new article of manufacture comprising a cast cut having ribs formed on the back thereof and integrally

therewith, whereby the cut can be secured to the printing segment;

(3) To provide a cut for use on cylindrical printing segments which can be cast by means of the ordinary matrices used for 60 making flat cuts or prints for newspapers or other similar publications;

(4) To provide a cut for the cylindrical printing segments of a multigraph machine which can be easily and quickly made; and 65

(5) To provide a new and novel casting machine for casting the cuts referred to above.

Other objects will appear as this description progresses, references being had to the 70 accompanying drawings in which Figure 1 is a side elevation of my improved casting machine.

Fig. 2 is an end elevation thereon.

Fig. 3 is a transverse section, partially in 75 elevation, taken on line 3—3 of Figure 1.

Fig. 4 is a longitudinal section taken on line 4—4 of Fig. 2.

Fig. 5 is an enlarged longitudinal sectional detail showing a portion of the construction illustrated in Fig. 4 on an enlarged 80 scale.

Fig. 6 is an enlarged transverse sectional detail of a modified form of my invention.

Fig. 7 is a perspective view showing details of construction of a still further modification of my casting machine, and 85

Fig. 8 is a perspective view of a portion of a cut or print constructed in accordance 90 with my invention.

Throughout the several views similar reference characters will be used for referring to similar parts.

Referring for the present to Figs. 1 to 5 inclusive, my improved casting machine comprises a drag 10 which as shown in Figs. 2 and 3 is provided with a concave cylindrical inner surface which is adapted to receive and support a papier mâché matrix 11, such as is used in the preparation of prints or 100 cuts for newspapers and other similar publications. Trunnions 12 extend in opposite directions from the upper edges of the drag 10 and are journaled in bearings 13 carried at the upper ends of the brackets 14. The 105 brackets 14 are secured together by means of a cross-bar 15 as shown in Figs. 2 and 3.

A cope 16 having a convex cylindrical surface co-acts with the drag 10 to form an annular cylindrical space 16a between the cope 110

and drag for receiving the matrix and the molten metal which is to form the cut. It will, of course, be apparent that the radius of curvature of the convex surface of the cope is somewhat smaller than the radius of curvature of the concave surface of the drag.

Side spacing strips 17 and an end spacing strip 17^a (see Fig. 4) are used for properly spacing the cope from the drag and for defining the outline of the cut, that is, the size of the cut is determined by the distance between the side spacing strips 17 and the position of the end spacing strip 17^a which can be shifted longitudinally of the space between the cope and drag.

A pedestal 18 extends upwardly from each of the trunnions 12 and a cross-bar 19 is secured to the upper ends of the pedestal 18 by means of the nuts 20. The cross-bar carries a screw-threaded nut 21 into which is threaded a screw 22 having the handle 23 at its upper end. The lower end of the screw 22 is adapted to bear upon a bar 24 extending transversely of the cope. By means of the mechanism just described, the cope can be firmly clamped to the drag and then released when the casting operation has been completed so as to expedite the removal of the cut from the cope.

From an inspection of Figs. 4 and 5 it will be noticed that the cope is provided with an end member 25 which inclines upwardly away from the space between the cope and the drag and that the drag is provided with an outwardly extending flange 26 which inclines in an opposite direction from the end member 25 of the cope. These two members co-act, when the mold is tilted to the position shown in dotted outline in Fig. 4, to form a trough or channel for receiving and directing the molten metal into the space between the cope and the drag. If desired, the cope can be hinged to the drag as shown at 27 in Figs. 1 and 4. A pin 10^a is conveniently provided on the drag 10 to co-operate with a standard 10^b when the matrix is being assembled in the drag, the cope having of course been removed. The drag is thereby prevented from tilting during the make-ready operation.

As shown in Figs. 1 and 3, the cope is provided with spaced longitudinal extending T-shaped slots 28 which open outwardly through the convex surface of the cope into the space between the cope and drag. As many of these slots can be used as desired, but it is necessary to make the spacing thereof the same as the spacing of the T-shaped slots on the printing segment of the machine with which the cuts produced by my casting machine are to be used. For use with the commercial multigraph machine, I prefer to have the slots 28 spaced apart seven-eighths of an inch.

In using my improved casting machine,

the paper matrix bearing the impression which it is desired to reproduce by the cut is first placed in the drag, which is supported conveniently by the standard 10^b; the cope having been previously removed. The spacing strips 17 and 17^a are properly positioned, whereupon the cope 16 is then placed in position and the screw 22 manipulated to clamp the cope and drag together. The type metal having been melted, the cope and drag are tilted to the position shown in dotted outline in Fig. 4 and the molten metal poured into the trough formed by the end member 25 and the flange 26. The molten metal thereupon flows into the space between the cope and drag and quickly solidifies due to the chilling action of these two members. The screw 22 is thereupon manipulated to release the cope 16 which can be removed from the drag. The formed cut is thereupon removed from the cope by moving it lengthwise of the cope. The cut thus formed can be easily and quickly attached to a segment of a printing machine having slots of the same shape and size as the cut, by bringing the ribs formed on the back of the cut into registry with the ends of the slots and then moving the segment and cut longitudinally relatively to each other. A cut thus secured to a printing segment will not shift during the printing operation. It will, of course, be apparent that the cost of producing a cut by the method described above is much less than the cost of producing a cut by means of the electrotype process, and that the cuts can be easily and quickly made whenever they are desired.

In order to prevent the cut formed by the process described above from sticking to the mold, I prefer to apply thin cocoanut oil or some other similar material to the surfaces of the cope which come into contact with the cut.

On account of the comparatively small dimensions of the slots formed in the cope, and because of making these surfaces very smooth, I prefer to construct the cope in the manner shown in Fig. 6, wherein the reference character 16' indicates a convex cylindrical member having longitudinally extending slots 28' milled therein. I then secure to the convex surface of the member 16' by means of the screws 30 or any other suitable means, a strip of metal which thereafter has the slots 28'' milled longitudinally thereof and in registry with the slots 28', thereby forming a plurality of strips, 31, the edges of which are in spaced relation and overhang the sides of the slots 28', thus forming the necks of the T-shaped slots. The strips 31 are preferably formed of metal which can be flexed as such a construction permits a slight flexure of the strips during the separation of the formed cut from the cope which facilitates this separation. If

for any reason it becomes necessary, the screws 30 can be manipulated to release the strips 31 from the member 16' of the cope, thus permitting the strips 31 to be removed 5 from the member 16' along with the formed cut. The strips 31 can then be individually removed or separated from the cut.

In Fig. 7 I have illustrated a further modification in the construction of the cope 10 wherein the sides 32 of the grooves 28' in the member 16' are beveled or inclined outwardly. This not only facilitates the removal of the formed cut from the cope but produces a cut in which the sides of the 15 heads of the ribs are beveled as shown in Fig. 8. The thin edges thus produced on the edges of the heads of the ribs will conform themselves to any irregularities on the walls of the slots with which they are to 20 co-act, and will also compensate for small variations in the spacing of the ribs due to slight irregular contractions which may occur during the casting of the cut.

While I have described the details of construction of the preferred embodiment of my 25 improved casting machine and the cut formed thereby, it is to be clearly understood that my invention is not to be limited to these details of construction but that it is 30 capable of modifications and also other adaptation within the scope of the appended claims.

Having thus described my invention, what I claim is:

1. A casting machine comprising a drag 35 having a smooth concave cylindrical surface, and provided at its opposite sides with trunnions extending outwardly therefrom, the axis of said trunnions extending trans- 40 versely of said drag, a support having bearings for said trunnions, a cope having a convex surface for co-acting with the concave surface of said drag, the radius of said cope being less than the radius of said drag, the 45 said cope having spaced T-shaped slots extending longitudinally thereof and opening through the said convex surface towards said drag, means for holding the co-acting surfaces of said drag and cope in spaced relation, 50 a cross-bar supported by said drag, a screw threaded through said cross-bar and having its inner end bearing against said cope, the said cope and drag being provided with co-acting oppositely inclined members 55 at one end thereof for receiving and directing molten metal between said cope and drag.

2. A casting machine comprising a drag 60 having a smooth concave cylindrical surface, and provided at its opposite sides with trunnions extending outwardly therefrom, the axis of said trunnions extending trans- 65 versely of said drag, a support having bearings for said trunnions, a cope having a convex surface for co-acting with the con-

cave surface of said drag, the radius of said cope being less than the radius of said drag, the said cope having spaced T-shaped slots extending longitudinally thereof and opening through the said convex surface towards 70 said drag, means for holding the co-acting surfaces of said drag and cope in spaced relation, and means for clamping said cope and drag together, the said cope and drag being provided with co-acting oppositely inclined 75 members at one end thereof for receiving and directing molten metal between said cope and drag.

3. A casting machine comprising a drag 80 having a smooth concave cylindrical surface, means for pivotally supporting said drag to rotate about an axis extending transversely of said drag, a cope having a convex surface for co-acting with the concave surface of said drag, the radius of said cope 85 being less than the radius of said drag, the said cope having spaced slots extending longitudinally thereof and opening through the said convex surface towards said drag, and means for holding the co-acting surfaces of said drag and cope in spaced relation, means for clamping said cope and drag together, the said cope and drag being provided with co-acting oppositely inclined 90 members at one end thereof for receiving and directing molten metal between said cope and drag.

4. A casting machine comprising a drag 95 having a smooth concave cylindrical surface, means for pivotally supporting said drag to rotate about an axis extending transversely of said drag, a cope having a convex surface for co-acting with the concave surface of said drag, the radius of said cope 100 being less than the radius of said drag, the said cope having spaced slots extending longitudinally thereof and opening through the said convex surface towards said drag, means for holding the co-acting surfaces of 105 said drag and cope in spaced relation, and means for clamping said cope and drag together.

5. A casting machine comprising cope 110 and drag members, one of which is provided with a smooth concave cylindrical surface, and the other of which is provided with a convex cylindrical surface having a smaller radius than said concave cylindrical surface, the member having the concave cylindrical surface being provided with 115 spaced T-shaped slots extending longitudinally thereof and opening through said convex surface, the edges of the heads of said slots being beveled outwardly, means for holding said cope and drag members in 120 spaced relation, and means for pivotally supporting said members to rotate about an axis extending transversely of the axis of said cylindrical surface.

6. A casting machine comprising cope 130

- and drag members, one of which is provided with a smooth concave cylindrical surface, and the other of which is provided with a convex cylindrical surface having a smaller radius than said concave cylindrical surface, the member having the convex cylindrical surface being provided with a slot extending longitudinally thereof and opening through said convex surface, means for holding said cope and drag members in spaced relation, and means for pivotally supporting said members to rotate about an axis extending transversely of the axis of said cylindrical surface.
15. 7. A casting machine comprising cope and drag members, one of which is provided with a smooth concave cylindrical surface, and the other of which is provided with a convex cylindrical surface having a smaller radius than said concave cylindrical surface, the member having the convex cylindrical surface being provided with spaced slots extending longitudinally thereof and opening through said convex surface, and means for holding said cope and drag members in spaced relation.
8. A casting machine comprising cope and drag members, one of which is provided with a smooth concave cylindrical surface and the other of which is provided with a co-acting convex cylindrical surface, the said last named member having spaced T-shaped slots extending longitudinally thereof and opening through said convex surface, the edges of the heads of said slots being beveled outwardly.
9. A casting machine comprising cope and drag members, one of which is provided with a smooth concave cylindrical surface and the other of which is provided with a co-acting convex cylindrical surface, the said last named member having a T-shaped slot extending longitudinally thereof and opening through said convex surface, the edges of the head of said slot being beveled outwardly.
10. A casting machine comprising two members having co-acting complementary cylindrical surfaces forming an annular cylindrical space, one of said members being provided with a longitudinally extending slot opening into said space.
11. A casting machine comprising cope and drag members, one of which is provided with a cylindrical surface, the other of said members comprising a member having a convex cylindrical surface and having a slot extending longitudinally thereof and opening through said convex surface, a strip of flexible metal secured to said last named member on each side of said slot, the edges of said strips being in spaced relation, but overhanging the sides of said slot, whereby a T-shaped slot is formed in said last named member.
12. A casting machine comprising cope and drag members, one of which is provided with a cylindrical surface, the other of said members comprising a member having a convex cylindrical surface and having a slot extending longitudinally thereof and opening through said convex surface, a strip of metal secured to said last named member on each side of slot, the edges of said strips being in spaced relation, but overhanging the sides of said slot, whereby a T-shaped slot is formed in said last named member.
13. A casting machine comprising cope and drag members one of which is provided with a cylindrical surface, the other of said members comprising a member having a convex cylindrical surface and having a slot extending longitudinally thereof and opening through said convex surface, a strip of metal, and means for detachably securing said strip of metal to said last named member with the edge thereof extending over the side of said slot.
14. A casting machine comprising cope and drag members one of which is provided with a convex cylindrical surface having a slot extending longitudinally thereof, and a pair of flexible metal strips secured to said convex member with their adjacent edges in spaced relation and overhanging the sides of said slot, whereby a T-shaped slot extending longitudinally of said convex member is formed.
15. A casting machine comprising a member having a convex cylindrical surface and having a T-shaped slot extending longitudinally thereof with the neck of the slot extending through the convex surface of said member.
16. A casting machine comprising a member having a convex cylindrical surface and having a T-shaped slot extending longitudinally thereof with the neck of the slot extending through the convex surface of said member, the portions of said member defining the inner sides of the head of the T, being movable with respect to the remaining portions of said member whereby the disengagement of the cut from said member is facilitated.
- In witness whereof, I hereunto subscribe my name this 12th day of July, 1920.
